UNITED STATES PATENT OFFICE.

CLARENCE E. DOOLITTLE, OF ASPEN, COLORADO.

DISCHARGE-NOZZLE AND VALVE THEREFOR.

SPECIFICATION forming part of Letters Patent No. 595,014, dated December 7, 1897.

Application filed April 7, 1897. Serial No. 631,190. (No model.)

To all whom it may concern:

Be it known that I, CLARENCE E. DOOLITTLE, a citizen of the United States, residing at Aspen, in the county of Pitkin and State 5 of Colorado, have invented certain new and useful Improvements in Discharge-Nozzles and Valves Therefor; and I do hereby declare the following to be a full, clear, and exact description of the invention, such as will enable 10 others skilled in the art to which it appertains to make and use the same.

My invention relates to discharge-nozzles such as employed for applying power to water-wheels, but has particular reference to the 15 controlling-valves used in connection therewith.

As a primary object the invention contemplates a most economical and effective utilization of the propelling-stream under all conditions of work imposed upon the wheel. To 20 this end a double valve is provided the gate-plates whereof work synchronously, but in opposite directions, over the end of their nozzle. These gate-plates are in controllable 25 communication with a suitable governor, thus automatically regulating the volume of water discharged. They are also by preference vertically arranged and operate from center to circumference of the nozzle, so that the driving- 30 stream is at all times projected upon the wheel-blades or buckets in a direction tangent to the wheel itself.

As a further object the foregoing construction comprises a valve mechanism peculiarly 35 sensitive and responsive in its operation—a most important quality, especially when used in connection with electrical appliances and machinery.

The invention will be hereinafter more particularly described, and pointed out in the 40 claims following.

In the accompanying drawings, which form part of this specification and whereon like letters of reference indicate corresponding 45 parts in the several views, Figure 1 represents a side elevation of my invention shown in its operative relation to a section of water-wheel rim. Fig. 2 is a front elevation of nozzle with gate-plates and beveled gearing for 50 actuating said plates over the end of nozzle. Fig. 3 is a central horizontal section taken on the line 3 3 of Fig. 2. Fig. 4 is a plan view

of parts shown by Fig. 2. Fig. 5 is a central vertical section taken on the line 5 5 of Fig. 4; and Figs. 6 and 7 are detached detail views 55 illustrating in perspective the main side arms or supports for each gate-plate, together with the integral segment-gear by which actuated.

Reference being had to the drawings and letters theron, A is a fragmentary view of a 60 water-wheel rim, and B indicates a discharge-nozzle located adjacent thereto, as shown by Fig. 1. The nozzle B, which has converging walls a, is in communication with a suitable source of water-supply, (not shown,) and at 65 one side is indented by a depression b, constituting a seat for the extremity of a horizontal valve-stem C. Keyed to the rotatable stem C is a bevel-gear D for purposes that will later appear, while the opposite end of 70 said stem C finds bearings in a fixed cap, serving also as means for preventing a longitudinal movement thereof. Above and below nozzle B, diametrically opposite each other, are integral lugs c with squared surfaces, 75 (best shown by Fig. 5,) into which are screwed upper and lower vertical studs E F, respectively. These studs are counterparts one of the other, each having a central reduced portion d and a further reduced screw-threaded 80 extremity e, the latter to receive a retaining-nut f.

Upon the main body portion of upper stud E and the reduced portion d of lower stud F are rotatably mounted coacting side arms G 85 H, which converge toward their outer ends and swing in a curve coincident with the extremity of nozzle B, having the studs aforesaid for its center, while upon the reduced portion d of same upper stud E and the main 90 body portion of same lower stud F is mounted a second coacting pair of side arms I J of similar construction and of corresponding action. These side arms G, H, I, and J, thus journaled upon opposite sides of nozzle B, are 95 connected in pairs by corresponding gate-plates K L, each dressed upon the under surface to conform with the curved extremity of nozzle B, reinforced upon the upper surface by a strengthening-rib g, and detachably retained in place by cap-screws h. The outside arms I and H of each pair differ from their mates G and J in the addition to each 100 of a segment-gear M N, by preference cast

integral with each of said arms, respectively, having beveled teeth *i* extending to one side and meshing with those of the beveled gear D, fixed upon valve-stem C, whereby said 5 segment-gears and dependent parts may be oscillated in either direction.

In the construction of a nozzle and its valve according to this invention it will be observed that the shoulders formed upon studs E F at 10 the intersection of their reduced portions *d* serve to prevent friction between the adjacent side arms of each pair, and by the jamming of nuts *ff* all of said arms G, H, I, and J may be locked in closed relation, while their 15 ends and the end of nozzle B are all turned up in a lathe together. It will be noted further that gate-plates K and L are then affixed to their respective side arms in a detachable manner, thus providing a convenient means 20 for resurfacing their seats when worn or for the substitution of new plates.

It may be further stated as an advantageous consequence of the peculiar arrangement and combination of parts heretofore 25 shown and described that the increased efficiency of the present valve is due in no small degree to the relative position occupied by gate-plates K L and the nozzle B—that is to say, the manner of pivoting the former 30 upon the latter. By reference to Figs. 4 and 5 in particular it will be observed that the plates K, L aforesaid are each supported and carried by a pair of side arms G H and I J, which latter are pivotally connected to the 35 nozzle B by means of studs E F, projecting upon opposite sides thereof in a common plane passing through the axis of the nozzle. By this arrangement friction is reduced to a minimum and occurs almost exclusively at 40 the bearings of said side arms upon their respective studs, the latter being especially designed and adapted to withstand all strains incident to valves of this character. In other words, the present invention embodies a pair 45 of swinging valves or gate-plates working over the end of a nozzle in opposite directions upon a curve having for its center their pivotal points, which points are also in the longitudinal center of the nozzle, thus insuring 50 the greatest ease and accuracy of operation under all conditions of work imposed upon the nozzle or water-pressure therein.

The practical operation of my invention as embodied in the present drawings is as follows: Presuming that one or more discharge-nozzles are located with reference to a water-wheel, as indicated by Fig. 1, having the discharge-slot between gate-plates K L arranged in the same plane as that of the wheel; also, 55 that the valve-stem C is adapted to rotate one way or the other under influence of a suitable governor; and presuming, further, that a maximum load has been imposed upon wheel A and that as a consequence the nozzle B is 60 wide open, projecting a driving-stream of water in a true tangential direction upon the buckets of wheel A; if now the load upon wheel 65

A is for any cause reduced the governor (not shown, but incident to all such machinery) automatically and instantly serves to rotate 70 valve-stem C and through same its fixed gear D, which latter in turn communicates a like motion from its opposite sides, but in reverse directions, to the segment-gears M N. The gears M N then operating through their respective side arms I H serve to simultaneously 75 close gate-valves K L toward the center of discharge-nozzle B, thus reducing the volume of water discharged until an equilibrium is 80 established between the power required and the force applied to the wheel. The reverse action of that last described is equally true and apparent, so that said gate-plates under influence of the governor are automatically 85 opened or closed much or little, according to requirements, without in the least detracting from the efficiency of the wheel. The driving-stream is in no manner deflected by a partial closing of the controlling-valve, but, on the contrary, maintains a direction tangential to 90 the wheel-rim under all conditions and delivers directly upon its buckets without waste or undue wear upon the wheel.

The foregoing being substantially a description of my invention in its preferred form of 95 construction it will be noted that various changes in such construction and in the arrangement of parts may be made and substituted for those herein shown and described without in the least departing from the spirit 100 of my invention as set forth in the following claims.

I claim—

1. In a discharge-nozzle the combination with a pair of gate-plates working in opposite 105 directions over the end thereof, of side arms supporting each of said plates pivotally connected to the nozzle in a plane passing through its longitudinal axis, substantially as described.

2. In a discharge-nozzle having a curved extremity, the combination with a pair of gate-plates working in opposite directions over the end thereof, of a pair of side arms supporting each of said plates pivotally connected to the nozzle in a common plane passing through the axis of the nozzle, and suitable gearing for rocking each pair of side arms with their respective gate-plates in reverse directions, substantially as described.

3. In a discharge-nozzle having a curved extremity, the combination with a pair of gate-plates working in opposite directions over the end thereof, of a pair of side arms supporting each of said plates pivoted upon the nozzle in a plane passing through its longitudinal axis as also at points coincident with the center of curvature described by said nozzle extremity, and suitable gearing interposed between said side arms for rocking them in reverse directions, substantially as described.

4. In a discharge-nozzle, the combination with a pair of gate-plates working in opposite

directions over the end thereof, of a pair of side arms supporting each of said plates, a coacting pair of studs upon which said arms are journaled projecting from sides of the nozzle in a plane which passes through its axis, and suitable gearing interposed between said side arms for rocking them in reverse directions, substantially as described.

5. In a discharge-nozzle, the combination
10 with a pair of gate-plates working in opposite directions over the end thereof, of a pair of side arms supporting each of said plates piv-

otally connected to the nozzle in a common plane passing through its axis, a segment-gear in communication with each pair of side 15 arms, and a rotatable gear-wheel in mesh with the segment-gears for actuating them in reverse directions, substantially as described.

In testimony whereof I subscribe my signature in presence of two witnesses.

CLARENCE E. DOOLITTLE.
